BUFFING WHEEL

Harvey E. Larsen, Steger, Ill., assignor to Steger Products Manufacturing Corporation, Steger, Ill., a corporation of Illinois

Application September 18, 1952, Serial No. 310,323

2 Claims. (Cl. 51—197)

1

This invention relates to buffing or abrading wheels, and more particularly, to an improved buffing wheel adapted for use in the machine-operated cloth-buffing of suitably pre-treated woodwork or furniture to impart thereto a lustrous finish.

Although the instant invention will be described in detail in connection with a preferred use therefor, namely, the buffing of pre-treated woodwork and the like, it will be appreciated that the instant buffing or abrading wheel may be used in many other similar operations. In the preparation of woodwork or furniture such as television cabinets, for example, the cabinet is fabricated of suitable wood and is usually then treated by the application of a lacquer coating or finish. The surface is usually also "wet-sanded" to remove roughness and irregularities of a coarse nature. Then, the surface is buffed to impart thereto the desired lustre.

Heretofore, it has been necessary generally to carry out the buffing operation by hand, because machine buffing resulted almost invariably in burning the finish and even the wood, by reason of the harsh action of the machine. Machine buffing, usually by means of a rotary rubbing motion of a suitably supported buffing cloth urging an abrasive rubbing compound against the surface to be buffed, is relatively inflexible to the extent that the machine cannot sense over-heating at the buffing surface. Accordingly, such cabinet buffing operations as were necessary were carried out by hand, using the usual pumice rubbing compounds ordinarily employed for such purposes.

In essence, the particular buffing operation here considered involves fine smoothing, by moderate abrasive action, so as to obtain a sufficiently smooth finished surface to impart thereto a lustrous appearance. Manual buffing, of course, is tedious and time-consuming. But, as just mentioned, it was heretofore not possible to exploit the advantages of speed, uniformity and facility of operation afforded by machine buffing, because over-heating or burning almost invariably resulted using those available buffing or rubbing compounds and the available buffing wheel assemblies.

The instant invention relates to a cloth-buffing wheel powered for rotary motion, which is adapted for use in a machine-operated cloth-buffing operation. Such a buffing wheel involves a suitable supporting structure or head having mounted on a circular face thereof, one or a plurality of layers of suitable resilient material,

2

such as sponge rubber. A buffing surface cloth is wrapped over the layer and resiliently supported thereby. Preferably, a sheep-skin is interposed between the cloth and the resilient layer.

It is, therefore, an important object of the instant invention to provide an improved cloth-buffing wheel structure.

It is a further object of the instant invention to provide an improved buffing wheel comprising a generally circular buffing wheel head, a resilient pad mounted on a face of said head, and a buffing surface cloth covering said pad and resiliently supported thereby.

It is another object of the instant invention to provide an improved buffing wheel comprising a buffing head adapted to threadedly engage a drive shaft for co-rotation therewith and having grooves cut in a face thereof, a sheep-skin overlying said face and secured to said head, a resilient backing member for said sheep-skin seated in said grooves for co-rotation with said head, and a buffing surface cloth covering said sheep-skin, resilient backing member and head.

It is still a further object of the instant invention to provide an improved mounting for a buffing wheel head comprising a resilient pad adapted to be mounted on an operating face of said head, a sheep-skin backed against said pad for covering the same, and a buffing surface cloth for wrapping the sheep-skin covered resilient pad.

Other and further objects, features and advantages of the present invention will become apparent to those skilled in the art from the following description of a preferred embodiment thereof, and the drawings accompanying the detailed description.

On the drawings:

Figure 1 is a plan view of the operating face of a buffing wheel head embodying the instant invention;

Figure 2 is a sectional view taken along a plane passing axially through a diameter of the buffing wheel embodying the instant invention;

Figure 3 is a plan view of the sheep-skin element employed in the instant buffing wheel assembly; and

Figure 4 is a sectional view taken substantially along the line IV—IV of Figure 3.

As shown on the drawings:

As shown in Figure 2, the instant buffing wheel indicated generally by the reference numeral 10 comprises a generally circular buffing wheel head 11, a resilient pad 12 mounted on a face 11a of the head 11, a sheep-skin cover 13 for the pad 12,

and a buffing surface cloth 14 covering the sheep-skin 13 and resiliently supported by the pad 12.

As shown in Figure 1, the buffing wheel head 11 is generally circular in shape, providing a generally disk-shaped wheel supporting structure presenting a generally circular flat operating face 11a on one side thereof. Actually, the wheel 11 comprises a central hub member 15 having a central threaded aperture 16, adapted to threadedly engage a suitable drive shaft (not shown). The threaded aperture 16 extends from the back or non-operating face 11b inwardly to communicate with a dish-shaped portion 17 on the front or operating face 11a of the head 11, so that a suitable lock nut or the like device (not shown) might be positioned within the dished portion 17 for coaction with the drive shaft (not shown) threadedly engaged in the aperture 16.

The hub member 15 also has a plurality of circumferentially spaced apertures or vents 18, which extend the full axial dimension of the hub 15, from the back face 11b to the front face 11a of the head 11 and which communicate with the central dished portion 17 via a generally annular recess 19 on the operating face 11a of the head 11.

It will be appreciated that ventilation and/or cooling of the central inside portion of the operating face 11a of the head 11 may be accomplished by the use of the apertures 18 in conjunction with air scoops or the like circulating devices, (not shown).

The hub 15 is preferably made of a suitably rigid structural material such as a metal casting. As shown in Figures 1 and 2, the hub 15 is suitably fitted with a generally annular collar 20, which fits snugly against a peripheral shoulder 15c on the back face 11b and an outwardly tapered extension or flange 15d on the front or operating face 11a of the hub 15. The annular collar 20 is itself outwardly tapered and it extends forwardly of the front face of the hub 15a to define a substantially flat annular front or operating face 11a for the head 11.

The collar 20 is made of a suitably strong supporting structure, although it preferably has a certain amount of resilience and may be made of hard or vulcanized rubber. Also, the collar 20 contains a plurality of generally radially extending grooves 21, which extend outwardly so as to become increasingly more shallow as they approach the periphery of the collar 20. Such grooves serve as a tread for receiving and co-rotatably mounting the porous or sponge rubber pad 12.

As is shown in Figure 2, the pad 12 may consist of one or a plurality of layers of resilient material such as porous or sponge (soft) rubber. The resilient pad 12 is cylindrical or disk-shaped, being substantially coextensive in area with the operating or front face 11a of the head 11 and being adapted to be mounted thereupon for co-rotation therewith. Actually, the resilient sponge rubber pad 12 is preferably slightly greater in area than the operating face 11a of the head 11, so that the back face 12b (Figure 2) of the pad 12 extends outwardly a slight distance beyond the periphery of the operating face 11a of the head 11. In this manner, the buffing wheel 10 is assured of suitable resilience during operating at the peripheral portions thereof.

Next, the sheep-skin cover 13 is resiliently backed or mounted by means of the resilient pad 12. The sheep-skin or the like fleece bearing

material 13 overlies the front face 12a of the resilient pad 12 (and also the front face 11a of the head 11) and extends over the peripheral portions of the pad 12 and the head 11 and overlies partially the back face 11b of the head 11.

As is best shown in Figures 3 and 4, the sheep-skin 13 comprises a hide-like or cloth-like backing member 13b which presents on the outer face thereof a suitable fleece-like wool material 13a (which is shown in the instant drawings as extending freely outwardly, for the sake of simplicity, but which actually is packed down substantially so as to form a resilient layer). The resilient wool layer 13a extends across the full area of the front face 12a of the pad 12 and back over the peripheries of the pad 12 and the head 11, at which point a suitable canvas or the like cloth sleeve 21 is sewed thereto, as by stitching 22. The sleeve 21 extends backwardly from the stitching 22 and is folded over at the rear edge thereof and stitched, as at 23. The folded over portion 21a of the sleeve 21 houses suitable tie cords, the ends 24 and 25 thereof extending freely from an opening in the folded over portion 21a.

As will be readily understood by those skilled in the art, the sheep-skin 13 is wrapped about the resilient pad 12, so that the sleeve 21 is positioned adjacent the back face 11b of the head 11, and the tie cord ends 24 and 25 are pulled tight and tied so as to secure the snug fit of the sheep-skin 13 against the pad 12, which in turn snugly fits the grooves 20a in the annular collar 20 for co-rotation therewith.

Referring again to Figure 2, next, the buffing surface cloth 14 is wrapped about the outer face 13a of the sheep-skin 13 and drawn snugly thereagainst, so as to wrap the surface cloth 14 around the periphery of the assembly 10 and against the back face 11b of the head 11. The buffing surface cloth 14 is then tucked underneath the sleeve extremity 21a, as at 14a, so as to secure the cloth 14 to the assembly 10, as will be well understood by those skilled in the art.

The buffing surface cloth may, of course, be made of any of a number of suitable buffing cloths such as cotton, flannel, or canvas cloths. In general, the particular cloth employed is preferably a non-fleece bearing cloth having a fabric working (outer) surface 14b.

It will thus be seen that the instant buffing wheel provides a number of distinct advantages over the prior art. For example, heat control and ventilation of the interior of the buffing wheel 10 may be provided not only by virtue of the various apertures in the hub 15, but also by "breathing" of the resilient rubber pad 12 during expansion and contraction thereof in response to various forces applied to the working face of the wheel 10. In addition, the substantial flexibility in the performance of the instant buffing wheel 10 is provided by the presence of at least three sources of resilient support, namely, the annular collar 20, the resilient pad 12 and the fleece or wool portion of the sheep-skin 13. All of such resilient means are suitably covered by the smooth fabric-surfaced buffing cloth 14, so that this cloth may cooperate suitably with the various rubbing compounds and, in addition, have the desired resilient backing for urging the same into operating position. Also, the layer of sponge rubber 12, which is of substantial axial thickness and which extends over the edges of the head 11, is uniquely adapted to provide a buffing surface which conforms to the shape of,

for example, a concave-surfaced article to be buffed.

It will be understood that modifications and variations may be effected without departing from the scope of the novel concepts of the present invention.

I claim as my invention:

1. A buffing wheel comprising a buffing head adapted to threadedly engage a drive shaft for co-rotation therewith and having grooves cut in a face thereof, a sheep-skin overlying said face and secured to said head, a porous rubber pad backing said sheep-skin seated in said grooves for co-rotation with said head, and a buffing surface cloth covering said sheep-skin, resilient backing member and head.

2. A buffing wheel comprising a buffing head adapted to threadedly engage a drive shaft for co-rotation therewith and having grooves cut

in a face thereof, a sheep-skin overlying said face and secured to said head, and a resilient backing member for said sheep-skin seated in said grooves for co-rotation with said head.

HARVEY E. LARSEN.
